(57) **CLAIM**

The ornamental design for a badge holder as shown and described.

DESCRIPTION

FIG. 1 is a front perspective view showing of a badge holder showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view showing of the badge holder in use state; and,

FIG. 10 is a rear perspective view showing of the badge holder in use state.

The broken lines in the figures illustrate portions of the badge holder that form no part of the claimed design, wherein the broken lines in a front surface and a rear surface near edges of a main body of the badge holder in FIG. 1 and FIG. 2 are shown stitching lines that form no part of the claimed design. The broken lines of ropes shown in FIG. 9 and FIG. 10 depict the environment and form no part of the claimed design.

1 Claim, 10 Drawing Sheets
